UNITED STATES PATENT OFFICE.

JAMES B. HARRISS, OF NEWARK, NEW JERSEY.

LAUNCHING AND LANDING OF AEROPLANES.

Application filed June 23, 1917. Serial No. 176,476.

To all whom it may concern:

Be it known that I, JAMES B. HARRISS, a citizen of the United States, residing at Newark, in the county of Essex and State 5 of New Jersey, have invented new and useful Improvements in the Launching and Landing of Aeroplanes, of which the following is a specification.

My invention relates to the launching and 10 landing of aeroplanes or the like, pertaining more particularly to means whereby flights may be made from and to vessels while under way or from and to other forms of predetermined stations.

15 Sea planes can readily rise or alight on the surface of the sea when the latter is comparatively smooth. Under such weather conditions the sea plane is simply lowered from the deck of the vessel to the surface of 20 the sea, after which the flight is made in the usual manner, the plane returning and being again drawn on board. Where, however, the vessel is moving at high speed it is more or less difficult to provide this action, and 25 where the sea is rough, such action is practically useless owing to the difficulty of the sea plane to rise under such conditions.

The present invention is designed for use 30 more particularly under such rough conditions and contemplates the use of means for launching the sea plane directly from the vessel without the use of a separate launching car, the means being so arranged as to permit the plane to readily and quickly 35 alight on return from the flight. The invention also contemplates the use of simple and efficient mechanism for accomplishing these ends.

To these and other ends, the nature of 40 which will be readily understood as the invention is hereinafter disclosed, said invention consists in the improved construction and combination of parts, hereinafter fully described, illustrated in the accompanying 45 drawings, and more particularly pointed out in the appended claims.

In the accompanying drawings, in which similar reference characters indicate similar parts in each of the views:

50 Fig. 1 is a diagrammatic view, in side elevation, of a war ship showing my invention

applied thereto in position to launch a sea plane.

Fig. 2 is a similar view showing the invention in position for alighting or landing 55 of the plane.

Fig. 3 is a plan view of a portion of the apparatus, showing a plane resting thereon at the end of the landing operation.

Fig. 4 is an edge view of the apparatus 60 of Fig. 3 in position at the beginning of the landing operation.

Fig. 5 is a front elevation of the apparatus in alighting formation.

Fig. 6 is a sectional view taken on line 65 6—6 of Fig. 5.

Fig. 7 is a view in side elevation of a portion of the apparatus in launching position.

Fig. 8 is a sectional view taken on line 70 8—8 of Fig. 7.

Fig. 9 is a sectional view taken on line 9—9 of Fig. 8.

Figs. 10 and 11 are sectional views taken 75 respectively on lines 10—10 and 11—11 of Fig. 7.

Fig. 12 is a detail view showing a modified arrangement.

Fig. 13 is a detail sectional view of parts shown in Fig. 12.

While the present invention is designed 80 more particularly for launching sea planes from vessels, it is applicable for use under other conditions, as for instance, the launching of aeroplanes or other forms of air ships from predetermined stations, and it is to 85 be understood that such various uses are contemplated by the invention. For purposes of illustration the invention is disclosed in a form for use in connection with war ships.

The general principles of the invention may 90 be understood from Figs. 1 and 2. The apparatus employed is in the form of a frame shiftable between the horizontal and vertical, and having a launching track with which mechanism carried by the pontoons of the 95 sea plane co-operate, launching taking place with the track extending substantially horizontally. After launching, the apparatus is manipulated to produce a landing structure, and the track shifted to the vertical. This 100 places the landing structure at a point where it may obstruct and check the flight of the

2
sea plane, the latter having a nose which contacts with the landing structure during flight. The track is then gradually lowered to the horizontal while the speed of the motor of the sea plane is gradually reduced, the shifting of the position of the landing structure bringing a supporting structure beneath the sea plane as the track approaches the horizontal. As a result, the sea plane can pass into contact with the landing apparatus while moving at a speed sufficient to sustain the plane, after which the motor speed of the plane can be readily reduced, since shifting of the track brings a mechanical sustaining element for the plane into action, so that the plane will come to rest by the time the track reaches its horizontal, the plane at this time being supported entirely by the landing structure.

20 As will be understood, specific structures for carrying out these general principles may be of different forms, and the invention is therefore not limited to the specific embodiment disclosed, the invention contemplated 25 plating such changes or modifications in structure as may fall within the spirit and scope of the invention as expressed in the claims when broadly construed.

In the embodiment shown, the structure is 30 more or less diagrammatically illustrated, and includes elements permanently carried by the vessel and elements permanently carried by the sea plane.

20 designates a support carrying a shaft 21 35 mounted in bearings 22, the shaft being adapted to be driven by suitable means such as a motor 23 through proper drive connections.

Connected to shaft 21 by a suitable connection, such for instance, as knuckle connection 24, are a pair of track-forming members 25, each member being in the form of an upper track element 25^a of suitable length, and a lower track element 25^b of less 45 length, these elements extending in parallelism and being maintained properly positioned by braces 25^c. As shown in Fig. 11, each track element is provided with an inwardly extending way or guide 26, these 50 guides opposing each other.

Co-operating with guides 26 are grooved rollers 27 carried by pontoons α of the sea plane A, any suitable connection between the pontoons and the rollers being employed, 55 a preferred arrangement being to mount each roller on a slideable support 28, said support including a cushioning device 29 which may act as a shock-absorber under certain conditions.

60 Co-operation between rollers 27 and the track members is had during the launching operation, at which time the track members extend in parallelism as indicated by the dot and dash lines α in Fig. 5, the tracks extending in a horizontal plane at this time.

When the plane is in position ready for launching, rollers 27 rest on track element 25^b at a suitable point removed from the free end of such element, the rollers being guided by ways 26. As the plane advances 70 under the action of its motor and acquires speed, the lifting planes of the sea plane are brought into action, raising the rollers into contact with the upper track element 25^a which thus forms a guide for the advancing sea plane. Track elements 25^b are of sufficient length to generally sustain the sea plane until the latter acquires a sufficient speed to sustain itself in flight, track element 25^a projecting beyond the advance end 75 of track element 25^b. Mounted on the upper face of track element 25^a adjacent to its advance end are a plurality of stop elements 30, these being adapted to co-operate with an arm 31 carried by each support 28, arm 31 and stops 30 being relatively positioned to be inactive when proper launching of the sea plane is had; should, however, the speed of the sea plane in advancing along the track, be insufficient to provide for the self-sustaining action of the plane, the plane will tend to fall when rollers 27 pass off of track element 25^b, at which time arms 31 contact with the upper face of track 25^a or with a stop 30, checking the plane while supporting it, so that the plane may be retained on the launching device and not become lost by passing from the device under a speed insufficient to sustain the plane within the air. The track members may be held in their 90 parallel relation in any suitable manner, the drawings, showing the use of a strap member 32 which acts to hold these members in this position. In addition, suitable guys 330 may be employed.

100 As shown in Fig. 1, the structure may be mounted at any suitable point of the vessel, this view showing the support as having a sufficient vertical length to locate the track, in horizontal position, above the turrets, the latter carrying a suitable support for the advance end of the track. Consequently the structure offers no obstruction to the use 110 of the guns.

115 During the launching operation, the space between the track members is practically unobstructed, so that the proper action of the lifting planes can be had. After launching has been completed, and it is desired to place the apparatus in condition for landing purposes, the track members are shifted to the full line position shown in Fig. 5, spreading or diverging the outer ends of the track members, this movement being permitted by the knuckle arrangement 24, strap 32 being manipulated to permit of the proper spread. Suitable net structures 33 and 34 are then mounted between the track members, preferably with resilient connections such as springs 35, after which the track structure 120 125 130

is raised to the vertical, as shown for instance in full lines in Fig. 2, the length of track element 25^a being preferably such as to place the net structures 33 and 34 at a point sufficiently above the superstructures of the vessel as to permit a clear approach by the aviator to these structures.

As shown in Figs. 3 and 4, the sea plane carries a suitable member 36 which practically forms a nose projecting in advance of the plane.

When the aviator desires to land, he drives the plane toward the net structures in such manner as to cause the nose to be brought into contact with net structure 33 which obstructs and checks the advance movement of the sea plane. When this takes place, the track structure is shifted toward the horizontal, thus presenting a resistance to the advance of the sea plane at its normal sustaining speed without, however, stopping the sea plane from advance movement. As the track structure lowers, the speed of the sea plane is reduced and net structure 34 becomes active to sustain the sea plane, so that the latter comes to rest while supported on the net structures.

In Fig. 12 I have shown a modified arrangement by means of which net structure 33 is pivotally mounted. In this figure 40 indicates a sleeve or cap adapted to be mounted at the outer end of each member 25, suitable detachable securing means, as for instance a pin 41, retaining the sleeve in position. 42 indicates a member pivotally connected to sleeve 40, member 42 carrying the devices to which net structure 33 is secured, it being understood that the sleeve and member structure is duplicated at opposite sides of the net so that the latter is suspended between the opposed member 42, the net structure extending on opposite sides of the points of pivotal connection. As a result, members 42 and the net structure constitute a frame swingingly mounted in sleeves 40 and presenting the yielding supported net. Weight structures may be made operative at the inner ends of members 42 in any manner, as by being adjustably supported on these members, as indicated at 43.

By this arrangement, net structure 33 will normally extend in a vertical plane regardless of the movement of the track structures. 55 When, therefore, the aviator contacts with the net structure and lowering of the apparatus begins, structure 33 will tend to maintain a vertical position and restrain the plane from moving off the apparatus. 60 Obviously, the sleeves and frame structure may be positioned on or removed from member 25 as a unit.

As heretofore pointed out, and as indicated in Figs. 1 and 2, the apparatus is 65 preferably located in such position that the

net structures are freely accessible to the returning aviator, and in such manner that the direction in which members 25 move when lowered will be that in which the vessel is moving. This arrangement is advantageous by reason of the fact that the advancing movement of the aeroplane is not entirely checked when contacting with the net structures. While checking of such movement may ensue where the advancing speed of the vessel is less than the minimum speed which will sustain the aeroplane in air, the abrupt change in advance movement is decreased in amount as the speed of the vessel approaches the minimum sustaining speed of the plane in flight. Hence, the rapidity of lowering movement of the landing mechanism may be decreased.

Such positioning is also of advantage in launching, enabling the aviator to more quickly obtain the flight-speed, thus permitting the use of a runway-forming frame of less length.

By the use of suitable block and tackle or crane mechanism, the plane may then be raised from the net structures, permitting the net structures to be removed and the track members to be shifted to normal launching positions, after which the plane may be properly positioned in the track structure ready for launching. To permit of ready positioning of the plane, rollers 27 may be arranged with a removable side 27^a (Fig. 10) which permits the plane to be placed in position and the track members then brought to launching position, after which the removable sides 27^a will be secured in position, thus placing the parts in proper position for launching.

As will be understood, the structure shown in the drawings is more or less diagrammatic, it being obvious that detail structural elements may require variation as to character and form in meeting the conditions presented by different types of installation. For instance, the particular form of the launching and landing mechanism may require one form when used in connection with vessels and a different form when used on land. Obviously, these changes will be readily apparent to the constructing engineer and are considered as falling within the spirit and scope of the invention.

Having thus described my invention, what I claim as new, is:

1. In apparatus for launching aeroplanes or the like of the pontoon type from predetermined stations, a plane runway including a pair of substantially parallel track members; each member comprising a pair of track elements, and rotatable members carried by the pontoon structure and movable with the plane, each rotatable member cooperating with a pair of track elements throughout the length of the latter in the

direction of plane launching movement to control the direction of plane movement while being launched.

2. In apparatus for launching aeroplanes or the like of the pontoon type from predetermined stations, a plane runway including a pair of substantially parallel track members, each member comprising a pair of track elements differing in length, and rotatable members carried by the pontoon structure and movable with the plane, each rotatable member co-operating with a pair of track elements throughout the length of the latter in the direction of plane launching movement to control the direction of plane movement while being launched.

3. In apparatus for launching aeroplanes or the like of the pontoon type from predetermined stations, a plane runway including a pair of substantially parallel track members, each member comprising a pair of vertically-aligned parallel elements, and rotatable members carried by the pontoon structure and movable with the plane, each rotatable member co-operating with a pair of track elements throughout the length of the latter in the direction of plane launching movement to control the direction of plane movement while being launched.

4. In apparatus for launching aeroplanes or the like of the pontoon type from predetermined stations, a plane runway including a pair of substantially parallel track members, each member comprising a pair of vertically-aligned parallel elements differing in length, and rotatable members carried by the plane, each rotatable member co-operating with a pair of track elements to control the direction of plane movement while being launched.

5. In apparatus for launching aeroplanes or the like from predetermined stations, a plane runway including a pair of substantially parallel track members, each member comprising a pair of vertically-aligned parallel elements differing in length with the element of greater length uppermost, and means carried by the plane and co-operating with the pairs of elements for controlling the direction of plane movement while being launched.

6. In apparatus for launching aeroplanes or the like from predetermined stations, a plane runway including a pair of substantially parallel track members, each member comprising a pair of vertically-aligned parallel elements differing in length with the element of greater length uppermost, and means carried by the plane and co-operating with the pairs of elements for controlling the direction of plane movement while being launched, said means including a rotatable member for each pair of elements, said rotatable member being initially supported by the lower element and by the upper ele-

ment when the member is freed from the support of the lower member.

7. In apparatus for launching aeroplanes or the like from predetermined stations, an aeroplane runway, rotatable members permanently carried by the aeroplane and co-operating with the runway for controlling the direction of aeroplane movement while being launched, and co-operating means carried by the runway and aeroplane for preventing movement of the aeroplane from off the runway when the speed of travel of the aeroplane is insufficient to sustain the aeroplane in flight.

8. In apparatus for launching aeroplanes or the like from predetermined stations, an aeroplane runway, rotatable members permanently carried by the aeroplane and co-operating with the runway for controlling the direction of aeroplane movement while being launched, and co-operating means carried by the runway and aeroplane for preventing movement of the aeroplane from off the runway when the speed of travel of the aeroplane at a predetermined point in its travel in the direction of length of the runway is insufficient to sustain the aeroplane in flight.

9. In apparatus for launching aeroplanes or the like from predetermined stations, an aeroplane runway, rotatable members permanently carried by the aeroplane and co-operating with the runway for controlling the direction of aeroplane movement while being launched, and co-operating means carried by the runway and aeroplane for preventing movement of the aeroplane from off the runway when the speed of travel of the aeroplane at a predetermined point in its travel in the direction of length of the runway is insufficient to sustain the aeroplane in flight, said means including a stop member carried by the runway, and an arm carried by the aeroplane, said arm being out of the plane of the stop member during normal launching action and movable into such plane when launching action is incomplete.

10. In apparatus for launching aeroplanes or the like from predetermined stations, an aeroplane runway, rotatable members permanently carried by the aeroplane and co-operating with the runway for controlling the direction of aeroplane movement while being launched, and co-operating means carried by the runway and aeroplane for preventing movement of the aeroplane from off the runway when the speed of travel of the aeroplane at a predetermined point in its travel in the direction of length of the runway is insufficient to sustain the aeroplane in flight, said means including a stop member carried by the runway, an arm carried by the aeroplane, said arm being normally out of the plane of the stop member during

normal launching action and movable into such plane when launching action is incomplete, and cushioning means rendered active when said stop member and arm are 5 brought into co-operating relation.

11. In landing apparatus for aeroplanes or the like, a frame shiftable from the vertical to the horizontal in the presence of the plane, and means carried by the plane adapted to contact with the frame during plane flight, said frame being shiftable during speed reduction of the plane motive power, whereby the frame will initially check the advance flight of the plane and present a 10 support therefor during the frame shifting movements.

12. In landing apparatus for aeroplanes or the like, a frame shiftable from the vertical to the horizontal in the presence of the 20 plane, said frame including a net structure, and means carried by the plane adapted to contact with the net structure during plane flight, said frame being shiftable during speed reduction of the plane motive power, whereby the net structure will initially check the advance flight of the plane and present a support therefor during the 25 frame shifting movements.

13. In landing apparatus for aeroplanes or the like, a frame shiftable from the vertical to the horizontal in the presence of the plane, said frame comprising a pair of members and a net structure yieldingly supported thereby, and means carried by the 30 plane and adapted to contact with the net structure during plane flight, said frame being shiftable during speed reduction of the plane motive power, whereby the net structure will initially check the advance 35 flight of the plane and present a support therefore during the frame shifting movements.

14. In landing apparatus for aeroplanes or the like, a frame shiftable from the vertical to the horizontal in the presence of the plane, said frame comprising a pair of members diverging toward their free ends and a net structure yieldingly supported thereby, and means carried by the plane and adapted 45 to contact with the net structure during plane flight, said frame being shiftable during speed reduction of the plane motive power, whereby the net structure will initially check the advance flight of the plane and present a support therefor during the 50 frame shifting movements.

15. In apparatus for launching and landing aeroplanes or the like, a frame adapted to form a plane support and shiftable between horizontal and vertical positions, said 60 frame and plane having complementary means whereby the frame, in horizontal position, will support the plane while being launched, and in vertical position, will 65 check the advance flight of the plane pre-

liminary to landing, the movement of the frame from its vertical to its horizontal position and in the presence of the plane causing the frame to form a support for the plane during speed reduction of the plane 70 motive power.

16. In apparatus for launching and landing aeroplanes or the like, a frame adapted to form a plane support and shiftable between horizontal and vertical positions, said 75 frame comprising a pair of track members positionable in parallel relation to form a plane runway during launching and being movable from such parallel position to present a diverging frame, and a net structure 80 positionable on said diverging frame and adapted to check the flight of the plane preliminary to landing and forming a support for the plane during the landing operation.

17. In landing apparatus for aeroplanes 85 or the like, a frame shiftable from the vertical to the horizontal in the presence of the plane, and means carried by the plane adapted to contact with the frame during plane flight, said frame being shiftable during 90 speed reduction of the plane motive power, whereby the frame will initially check the advance flight of the plane and present a support therefor during the frame shifting movements, said means including a swing- 95 ingly-supported net structure.

18. In landing apparatus for aeroplanes or the like, a frame shiftable from the vertical to the horizontal in the presence of the plane, and means carried by the plane adapted to contact with the frame during plane flight, said frame being shiftable during speed reduction of the plane motive power, whereby the frame will initially check the 100 advance flight of the plane and present a support therefor during the frame shifting movements, said means including sleeves detachably secured to said frame, and a net structure pivotally supported by the sleeves.

19. In landing apparatus for aeroplanes 110 or the like, a frame shiftable from the vertical to the horizontal in the presence of the plane, and means carried by the plane adapted to contact with the frame during plane flight, said frame being shiftable during 115 speed reduction of the plane motive power, whereby the frame will initially check the advance flight of the plane and present a support therefor during the frame shifting movements, said means including a swing- 120 ingly-supported net structure, said net structure having means for normally maintaining it in a substantially vertical plane.

20. In landing apparatus for aeroplanes or the like, a frame shiftable from the vertical to the horizontal in the presence of the plane, and means carried by the plane adapted to contact with the frame during plane flight, said frame being shiftable during 125 speed reduction of the plane motive power, 130

- whereby the frame will initially check the advance flight of the plane and present a support therefor during the frame shifting movements, said means including a swingingly-supported net structure, said net structure having means for normally maintaining it in a substantially vertical plane, said net structure being weighted to normally maintain it in a substantially vertical plane.
21. In apparatus adapted to permit landing of sea-planes or the like on moving vessels, a frame shiftable from the vertical to the horizontal and carrying means whereby the plane may be landed thereon, said frame being positioned on the vessel in such manner as to permit free contact of plane and said means when the frame is in vertical position, the frame movements toward the horizontal being in directions corresponding to the directions of advancing movement of the vessel.
22. In landing apparatus for aircraft, velocity checking means adapted to be located in an approximately vertical position in the path of the aircraft, and means for supporting said checking means so as to permit it to move in the same direction as that of the aircraft with decreasing speed as the aircraft's speed is checked.
23. In landing apparatus for aircraft, velocity checking means adapted to be located in substantially upright position in the path of the aircraft, and means for supporting said checking means so as to permit it to yieldingly move in the direction of flight of the aircraft and, at the same time, to move downwardly so as to present increased resistance to the advance of the aircraft, and simultaneously increased support beneath the aircraft as its velocity decreases.
24. In apparatus for launching aircraft from a predetermined station, the combination with an aeroplane including guide means hung from the plane, a runway at the station comprising track means, the guide means cooperating with the track means during plane launching movement, the said guide means and track means being relatively arranged to effect such cooperation when the plane acquires sufficient speed to sustain itself in flight, and cooperating provisions on the plane and track means for preventing plane launching when the speed of the plane is insufficient to sustain the aeroplane in flight.
25. In landing apparatus for aircraft, a substantially flat aircraft support, and means for yieldingly maintaining said support normally elevated and transverse to the path of the aircraft, said means permitting said support to simultaneously advance in the direction of movement of the airplane and also downwardly into substantially horizontal position.
26. In landing apparatus for aircraft, a substantially flat aircraft support, and means for yieldingly maintaining said support normally elevated and transverse to the path of the aircraft, said means permitting said support to simultaneously advance in the direction of movement of the airplane and also downwardly into substantially horizontal position under the impact of the aircraft, the construction being such that the forward and downward movement of said support is produced solely by the impact of the aircraft thereon.

In testimony whereof I have hereunto set my hand.

JAMES B. HARRISS.
